United States Patent Office

Des. 229,012
Patented Nov. 6, 1973

229,012

COVERED PITCHER

Dwight N. Wooters, Wooster, Ohio, assignor to Rubbermaid Sales Corp., Wooster, Ohio

Filed July 31, 1972, Ser. No. 276,830

Term of patent 7 years

Int. Cl. D7—01

U.S. CL. D7—65

FIG. 1

FIG. 2

FIG. 3

FIG. 4

FIG. 5

FIG. 6

FIG. 1 is a side perspective view of a covered pitcher embodying my new design.

FIG. 2 is an elevation of the opposite side thereof.

FIG. 3 is a top plan view thereof.

FIG. 4 is a front exploded elevation thereof.

FIG. 5 is a rear exploded elevation thereof.

FIG. 6 is a bottom plan view thereof.

I claim:

The ornamental design for a covered pitcher, as shown.
